SEWING KIT

Stanley Bindman, New York, N. Y., assignor to
Noma Electric Corporation, New York, N. Y.,
a corporation of New York

Application January 3, 1949, Serial No. 5

Term of patent 3½ years

(Cl. D3—19)

To all whom it may concern:

Be it known that I, Stanley Bindman, a citizen of the United States, residing at New York, Bronx county, and State of New York, have invented a new, original, and ornamental Design for a Sewing Kit, of which the following is a specification, reference being had to the accompanying drawing, forming part thereof.

Fig. 1 is a perspective view of a sewing kit embodying my new design, the kit being shown with the cover in open position, and

Fig. 2 is a similar view thereof as it appears in closed position.

I claim:

The ornamental design for a sewing kit, substantially as shown.

STANLEY BINDMAN.
